SKIP FOR HANDLING BULK FREIGHT

John W. Burnett, Chicago, Ill., assignor to Reynolds Metals Company, Richmond, Va., a corporation of Delaware

Application October 23, 1944, Serial No. 560,006

7 Claims. (Cl. 105—274)

1

My invention relates to an improvement in material handling equipment and has for one purpose to provide means for handling bulk materials of mixed sizes.

Another purpose is to provide an improved transporting and dumping skip for use, for example, with railway cars and trucks.

Another purpose is to provide an improved means for mounting such a skip on a car, truck or support.

Another purpose is to provide improved tilting and seating abutment means for skips and the like.

Other purposes will appear from time to time in the course of the specification and claims.

My invention is illustrated more or less diagrammatically in the accompanying drawings, wherein:

Figure 1 is a plan view;

Figure 2 is a side elevation;

Figure 3 is a section on an enlarged scale on the line 3—3 of Figure 2;

Figure 4 is a section on the line 4—4 of Figure 3;

Figure 5 is a section on the line 5—5 of Figure 2;

Figure 6 is a section on an enlarged scale on the line 6—6 of Figure 5; and

Figure 7 is a section on the line 7—7 of Figure 6.

Like parts are indicated by like characters throughout the specification and drawings.

Referring to the drawings, 1 generally indicates any suitable rails to receive the flanged wheels 2 of any suitable flat car 3 having the flat floor or deck 4. 5 are longitudinally extending wooden blocks or supports secured to the deck 4. 6 are transversely extending tieplates or strips which extend beneath the blocks 5 and terminate at opposite sides of the car floor 4. They may advantageously be recessed into the floor as shown in Figure 5. Referring to Figures 5 and 7, I illustrate at one end of the tie-plate or strip 6, a tipping stop generally indicated as 7 and having an upwardly extending abutment 8 having a generally arcuate inside pivoting surface 9. 10 is an upwardly extending back stop. The upwardly extending abutment 8 has an inclined face 11, the purpose of which will later appear. In Figure 5, I illustrate at the opposite end of the tie-plate or strip 6 an identical stop element 7a, which is shown as functioning as a seating guide. Note that the inclined face 11a of the upwardly extending member 8a faces toward the center of the car, whereas the corre-

2

sponding surface 11 of the stop 8 at the opposite end of the tie-strip faces outwardly. Any suitable number of tie-strips and stop assemblies may be employed but I find it convenient to use two for each individual skip.

Positioned above said pair of tie-plates or strips 6 is a skip structure generally indicated as A. Each said skip includes a bottom 15, side walls 16 and, in the form of Figure 5, an end wall 17. For reinforcement I may employ a plurality of any suitable exterior structural elements 18, herein shown as I-beams, bent or spliced to conform to the rounded corners 19, connecting the bottom 15 and the sides 16. These I-beams are sized and spaced to penetrate between the longitudinally extending blocks 5, with enough clearance to permit tilting.

The end of the skip opposite the wall 17 is closed by a door 20 hinged as at 21 and, if desired, provided with a limit chain 22. The door is shown in Figure 5, in full line, in the closed position and may be locked closed by any suitable means. I illustrate for example locking plates 23 secured to each of the side walls 16. Each plate 23 has a forwardly extending pin 24 apertured as at 25 and projecting through an aperture 26 in the door 20. 27 is any suitable locking wedge which may be dropped through the aperture 25.

30 In Figure 5, I illustrate a hinged door 20 at one end only of the skip and a closed end 17 at the opposite end of the skip. Thus the skip is built to be tilted and dumped in one direction only. The pivot is provided by a tipping lug 30 projecting downwardly from any suitable abutment plate 31 secured to the bottom of the skip. The intermediate portion has a rounded surface 32 adapted to oppose the concave rounded surface 9 of the abutment 8. It is also provided with two downwardly or outwardly extending end ears 33 adapted to prevent relative lateral movement of the hinge elements thus provided. When the skip has been tilted, rearward movement of the tipping lug or lock 30 is prevented by the upwardly extending stop 10. Any suitable means may be employed for tilting the skip. I illustrate for example an eye 35 adapted to receive any suitable chain, rope or cable whereby, from any suitable hoist not herein shown, the right hand end of the skip may be raised, referring to the position of the parts shown in Figure 5. The left hand end then tilts about the center provided by the engagement of the tipping lug 30 with the tipping abutment 8. It will be understood, that before, during or after tilting

movement, the gate 20 may be released to its dotted line position, both to permit the discharge of the material from the skip and to serve as a chute for directing it outwardly away from the track. When the skip is returned to its original position, a seating abutment or guide 40 engages the face 11a of the member 8a and guides the parts into their original position in which they are shown in Figures 5 and 10.

It will also be understood that if it is desired to provide a skip which tilts at both ends, the abutment assembly 7a shown at the right hand end of Figure 5, including 8a, 9a, etc. is reversed, so that the face 11a will face out instead of in. Then in the place of the seating guide 40, a second tipping hook assembly 30, 31 is secured to the bottom of the skip. A separate hoist or lifting means is provided for each end of the skip, and an assembly is thus provided which permits a skip, having a releasable door at each end, to be tilted selectively to dump at either side of the car or track.

It will be realized that whereas I have described and illustrated a practical and operative device, nevertheless many changes may be made in the size, shape, number and disposition of parts without departing from the spirit of my invention. I wish, therefore, that my description and drawings be taken as in a broad sense illustrative or diagrammatic, rather than as limiting me to my precise showing.

For instance, whereas I have shown my skip or skips as applied to a flat top rail car, I may employ it on other supports or carriers. I may employ it for example on motor trucks. It will be understood also that the hinge and locking details can be widely varied.

The use and operation of the invention are as follows:

Assume that it is desired to handle bulk materials, as for example in connection with a mine. One or more open topped skips are mounted on any suitable support such as a motor truck, or preferably a railroad car. The skip may receive the material to be handled, which is delivered through into the open top of the skip from any suitable delivery or dumping or conveyor means. The weight of the material in the skip is supported by the top floor of the car and also by the blocks 5. The car, after the skip or skips are filled, is moved to any suitable point of disposal and the skips are dumped by merely raising the end of the skip opposite to the door which is to be opened. While the particular hinge means may be widely varied, I find that the hinge abutments herein shown, including the tipping stop 8 and the tipping lock 30 are highly advantageous for several reasons. In the first place they are adapted to be used at each end of a double ended skip, and can alternatively serve as a tilting abutment or hinge and as a positioning or seating means. Also they are so formed as to prevent unintended endwise movement of the skip along the car when the skip is not tilted, because of the outwardly extending projections 33. An advantage of employing a plurality of skips is that I may simultaneously handle materials of different nature or different size or grade. It is thus possible to deliver a number of materials or grades or sizes of material upon a single flat car, they being picked up at the same point or various points, and being discharged either at one point or at various points.

My structure lends itself well to the employment of lighter materials or metals, such as

aluminum, and is so proportioned and designed that it can be made of aluminum or aluminum alloys. It will be understood, however, that I do not wish to be limited to the use of any particular material or metal, as a wide range of metals may be employed.

I claim:

1. A hinge and abutment connection for a skip including a tipping stop member adapted to be mounted upon a support, said stop member having an upwardly extending stop with a partly cylindrical concave pivot surface and a tipping hook adapted to be mounted on the lower side of a skip and including a downwardly extending hook portion having a lower convex face partly cylindrical in form and adapted to engage the partly cylindrical convex surface of the stop member in pivotal relationship, the tipping hook and the tipping stop member having portions which interpenetrate and are adapted to prevent their relative movement along the axis of tilt of the skip and a back stop element on the tipping stop member adapted to limit movement of the tipping hook away from the tipping stop.

2. In combination, a skip including side and bottom walls of sheet metal, a plurality of reinforcing members extending around the outside of the skip in contact with the side and bottom walls, a platform adapted to support the skip, a plurality of spaced cushion members extending upwardly from the platform into the spaces between the reinforcing members, the depth of the reinforcing members and the cushion members being equal, the space between the cushion members being just sufficient to permit the reinforcing members to enter between them, whereby the bottom floor of the skip, when it is on the platform, is supported substantially throughout its entire area upon the cushion members and the reinforcing members.

3. In combination, a skip including side and bottom walls of sheet metal, a plurality of reinforcing members extending around the outside of the skip in contact with the side and bottom walls, a platform adapted to support the skip, a plurality of spaced cushion members extending upwardly from the platform into the spaces between the reinforcing members, the depth of the reinforcing members and the cushion members being equal, the space between the cushion members being just sufficient to permit the reinforcing members to enter between them, whereby the bottom floor of the skip, when it is on the platform, is supported substantially throughout its entire area upon the cushion members and the reinforcing members, fulcrum means interposed between the platform and the skip adjacent one side of the platform adapted to permit vertical rotational movement of the skip with respect to the platform, the space between the cushion members and the reinforcing members being such that rotational movement may take place without interference between the cushion and reinforcing members.

4. In combination, a skip including side and bottom walls of sheet metal, a plurality of reinforcing members extending around the outside of the skip in contact with the side and bottom walls, a platform adapted to support the skip, a plurality of spaced cushion members extending upwardly from the platform into the spaces between the reinforcing members, the depth of the reinforcing members and the cushion members being equal, the space between the cushion members being just sufficient to permit the reinforce-

ing members to enter between them, whereby the bottom floor of the skip, when it is on the platform, is supported substantially throughout its entire area upon the cushion members and the reinforcing members, means interposed between the skip and the platform adapted independent of the reinforcing members and the cushion members to prevent movement of the skip with respect to the platform in a direction perpendicular to the cushion members.

5. In combination, a skip including side and bottom walls of sheet metal, a plurality of reinforcing members extending around the outside of the skip in contact with the side and bottom walls, a platform adapted to support the skip, a plurality of spaced cushion members extending upwardly from the platform into the spaces between the reinforcing members, the depth of the reinforcing members and the cushion members being equal, the space between the cushion members being just sufficient to permit the reinforcing members to enter between them, whereby the bottom floor of the skip, when it is on the platform, is supported substantially throughout its entire area upon the cushion members and the reinforcing members, means interposed between the skip and the platform adapted independent of the reinforcing members and the cushion members to prevent movement of the skip with respect to the platform in a direction perpendicular to the cushion members and fulcrum means interposed between the skip and the platform to define a pivot line about which the skip may rotate, the clearance between the cushion members and the reinforcing members being such that rotation may take place without interference between them.

6. In combination, a skip including side and bottom walls of sheet metal, a plurality of reinforcing members extending around the outside of the skip in contact with the side and bottom walls, a platform adapted to support the skip, a plurality of spaced cushion members extending upwardly from the platform into the spaces between the reinforcing members, the depth of the reinforcing members and the cushion members being equal, the space between the cushion members being just sufficient to permit the reinforcing members to enter between them, whereby the bottom floor of the skip, when it is on the platform, is supported substantially throughout its entire area upon the cushion members and the reinforcing members, means interposed between the skip and the platform adapted independent of the reinforcing members and the cushion members to prevent movement of the skip with respect to the platform in a direction perpendicular to the cushion, the skip being free to be raised vertically from the platform without interference

by any of the elements interposed between the skip and the platform.

7. In combination, a skip including side and bottom walls of sheet metal, a plurality of reinforcing members extending around the outside of the skip in contact with the side and bottom walls, a platform adapted to support the skip, a plurality of spaced cushion members extending upwardly from the platform into the spaces between the reinforcing members, the depth of the reinforcing members and the cushion members being equal, the space between the cushion members being just sufficient to permit the reinforcing members to enter between them, whereby the bottom floor of the skip, when it is on the platform, is supported substantially throughout its entire area upon the cushion members and the reinforcing members, means interposed between the skip and the platform adapted independent of the reinforcing members and the cushion members to prevent movement of the skip with respect to the platform in a direction perpendicular to the cushion members and fulcrum means interposed between the skip and the platform to define a pivot line about which the skip may rotate, the clearance between the cushion members and the reinforcing members being such that rotation may take place without interference between them, the skip being free to be raised vertically from the platform without interference by any of the elements interposed between the skip and the platform.
